[57]

CLAIM

The ornamental design for a rim for a lavatory, as shown and described.

DESCRIPTION

FIG. 1 is a top front perspective view of a rim for a lavatory showing my new design;

FIG. 2 is a top plan view thereof;

FIG. 3 is a cross sectional view taken along line 3—3 of FIG. 2; and,

FIG. 4 is a cross sectional view taken along line 4—4 of FIG. 2.

The broken line fragmentary representation of holes in FIGS. 1 and 2 and the representation of a countertop in FIG. 1 are for purposes of illustration only and form no part of the claimed design.
